CLAIM

I claim the ornamental design for an ice pack label, as shown and described.

DESCRIPTION

FIG. 1: is a perspective view of an ice pack label, showing my new design;

FIG. 2: is a front view thereof;

FIG. 3: is a back view thereof;

FIG. 4: is a left side view thereof;

FIG. 5: is a right side view thereof;

FIG. 6: is a top view thereof; and,

FIG. 7: is a bottom view.

The broken lines in the figure drawings show environment and form no part of the claimed design.

1 Claim, 5 Drawing Sheets
